UNITED STATES PATENT OFFICE.

COMMODORE PERRY BATEMAN, OF EXIRA, IOWA.

WAGON-BRAKE BLOCK.

SPECIFICATION forming part of Letters Patent No. 376,404, dated January 10, 1888.

Application filed October 19, 1887. Serial No. 252,818. (No model.)

To all whom it may concern:

Be it known that I, COMMODORE PERRY BATEMAN, a citizen of the United States, residing at Exira, in the county of Audubon and State of Iowa, have invented certain new and useful Improvements in Wagon-Brake Blocks; and I do hereby declare the following to be a full, clear, and exact description of the invention, such as will enable others skilled in the art to which it appertains to make and use the same.

My invention relates to improvements in wagon-brakes; and the object thereof is to provide simple and effective means for securing to said brake the leather facing-strip.

To this end my invention consists in a block provided with a yoke, which latter carries clamping-plates, all as will be more particularly described in the specification, and pointed out in the claims. I attain these objects by the device illustrated in the accompanying drawings, in which—

Figure 1 is a side elevation; Fig. 2, a plan view, but showing the yoke in section; Fig. 3, a detail showing the clamping-plates.

Similar letters of reference refer to similar parts in the several views.

A represents the block, B the yoke, and D the clamping-plates.

The plates D have rough contacting faces d' , and are provided at their ends with notches d , and are adapted to be carried by and to slide freely between the arms b of the yoke B.

The yoke B is attached to the block at b' and is provided with set-screws b' .

To operate the device it is only necessary to slightly separate the plates D, insert between them the end of the facing-strip C, and then by means of the set-screws b' firmly clamp the whole together. The rough faces of the plates 40 D will insure a firm grip on the strip C, and thus avoid any liability of the latter being displaced or withdrawn by the frictional contact of the wheel.

The facing-strip C is preferably made of 45 leather; but any other material that will make a good frictional contact with the wheel may be employed.

In Fig. 1 the clamping device is only shown at one end of the block, whereas in practice 50 there is one at each end; but, being duplicates, further showing is deemed unnecessary.

Having thus fully described my invention, what I claim as my invention, and desire to secure by Letters Patent, is—

1. The combination, with the block A, of the yoke B, clamping-plates D, having rough contacting faces d' , and the facing-strip C, substantially as described.

2. In a brake of the character described, the 60 combination of the yoke B, plates D, having rough contacting faces, and means for compressing the plates, all substantially as described.

In testimony whereof I affix my signature in 65 presence of two witnesses.

COMMODORE PERRY BATEMAN.
